UNITED STATES PATENT OFFICE.

SIMON ZUBROW, OF PHILADELPHIA, PENNSYLVANIA.

DESIGN FOR A BADGE OR LIKE ARTICLE.

Application filed February 9, 1926. Serial No. 16,456. Term of patent 3½ years.

To all whom it may concern:

Be it known that I, SIMON ZUBROW, a citizen of the United States of America, residing at Philadelphia, in the county of Philadelphia and State of Pennsylvania, have invented a new, original, and ornamental Design for a Badge or like Article, of which the following is a specification, reference being had to the accompanying drawing, forming a part hereof.

In the drawing:

Fig. 2 is a top plan view of the same.

I claim:

The ornamental design for a badge or like article, as shown.

SIMON ZUBROW.
